(57) **CLAIM**

The ornamental design for mezzanine connector housing, as shown and described.

DESCRIPTION

FIG. 1 is a front view of a mezzanine connector housing, showing our new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a first perspective view thereof;

FIG. 8 is a second perspective view thereof;

FIG. 9 is a reference disassembled perspective view indicating an example state of the mezzanine connector housing with a socket; and,

FIG. 10 is a reference perspective view indicating an example state of use thereof.

The broken lines shown in FIGS. 3, 4, 7 and 8 are for illustration only and do not form part of the claimed design. The socket in FIGS. 9 and 10 is provided to illustrate an environment related to the claimed design and forms no part of the claimed design.
